STAGE APPARATUS

Robert Lewis Geib, Los Angeles, Calif., assignor
to Warner Bros. Pictures, Inc., New York, N. Y.,
a corporation of Delaware

Application February 28, 1934, Serial No. 713,350

3 Claims. (Cl. 20—1,123)

This invention relates to improvements in theatrical stages. It is particularly useful in connection with the production of motion pictures wherein unusual effects are to be produced.

An object of the invention is to produce a scene that gradually increases in size giving a great production value in a small restricted area.

This is accomplished by providing a plurality of nested concentric telescoping stages or platforms upon which dancers or actors may perform. While using this system of telescoping stages unusual shots may be made wherein the eye of the camera sees at first one actor or actress standing on the outermost stage and gradually the camera view is increased as the stages are extended one above the other revealing other actors previously hidden behind the first actor.

Another object of the invention is to produce a scenic effect of a waterfall of gradually varying intensity. This is accomplished by providing each one of a plurality of stepped concentric stages with a remotely controlled hydraulic display system.

An advantage of this arrangement is that the camera may at first view what is apparently a solid body of falling water which gradually decreases in intensity to reveal an action component upon the concentric telescoping stages behind the fall of the water.

The concentric stages may be rotated in different directions at will to produce still further unusual effects in combination with the above-mentioned advantages.

Thus it will be seen that a vast number of unusual and pleasing scenes may be obtained in a small restricted space by the use of this apparatus.

For further details of the invention reference may be made to the drawings wherein:

Fig. 1 is a side elevation, partly in cross-section, of the hydraulic elevator and its associated turntables.

Fig. 2 is a side elevation in cross-section of one of the turntables showing the hydraulic arrangement carried thereby.

Fig. 3 is a fragmentary plan view showing the positions of the driving motors.

Fig. 4 is a side elevation of one of the driving motors.

Fig. 5 is a plan view of the driving motor shown in Fig. 4.

Fig. 6 is a diagrammatic view showing the relative positions of the lift arms, and rest members.

Fig. 7 is a side elevation of the controls for the hydraulic supply system.

Referring now to Fig. 1, the apparatus consists primarily of an extensible or collapsible support 1. Support 1 is composed of a hollow cylinder 2 mounted around and above a flange 3 integral

with a base plate 4. Base plate 4 projects from underneath cylinder 2, and rests on a concrete bed 5 to form a substantial supporting base for the apparatus. Bed 5 forms the bottom of a suitable elevator shaft or pit 6.

Concentric with cylinder 2 is a second hollow telescoping cylinder 7, the uppermost end of which is closed by a flange 8. Fastened to and depending from flange 8 is a hanger 9 which has a series of guide shoes 10, 11 and 12, adapted to contact alternately a series of guide rings, such as 13 and 14 mounted on the outside of the cylinder 2 thus ensuring a steady movement of the hanger 9 during movement of the cylinder 7.

The bottom end of the cylinder 7 is mounted around a flange 16 projecting above a screw-threaded base member 15 to form a piston head. The screw 15 mates with a collar 17 which in turn supports a second collar 18. Around the head of the collar 18 is mounted a leather washer 19 in contact with the walls of the cylinder 2. A retainer ring 20 rests on and positions the leather washer 19.

A second leather washer 21 is supported by ring 20. A spacer ring 22 rests on the leather 21 and is held in place by a piston spacer 23 mounted on the annulus of the piston 7. Supported on the top of piston spacer 23 is a piston guide 24 upon which rests a third leather washer 25 securely held in place by a retaining ring 26. These elements form a compact piston head for the cylinder 7.

The upper end of the cylinder 2 is closed by means of a guide bushing 27 having a suitable form of packing 28 held in place against the walls of the cylinder 7 by a packing gland 29. A retaining ring 30 integral with the top of the cylinder 2 serves as a base for a screw stud 31 which in turn holds the packing gland 29 in place.

An aperture 32 adjacent the base of cylinder 2 permits the entrance of a feed pipe 33 through which liquid under pressure may be applied to the piston head of the cylinder 7. Air vents such as 160 are placed in the cylinder 2 adjacent the ring 30, to permit the free passage of air into the space between the cylinders 2 and 7 above the piston head of the cylinder 7. Pipe 33 also serves as an outlet pipe for the liquid when pressure is released, and thus the cylinder 7 will be returned to its normal position by gravity.

The hanger or truss 9 consists of a series of spaced steps 34, 35, 36 and 37 which are connected together and held rigid by means of suitable cross-arms or struts such as 39 and 40. A bracket 42 is mounted on an arm 41 depending from the lowermost step 37. A guide wheel 43 is supported by and rotates about a bearing 44 suitably mounted on the bracket 42. Guide wheel 43 is adapted to traverse a vertically supported channelled guide rail 45, to prevent rotation of

and add stability to the member 9 and its associated parts.

A pair of rails 46 rest on the uppermost step 34 and support a car 47 through a series of wheels such as 48 resting on and adapted to traverse the rails 46. The car 47 forms the innermost one 49 of the concentric turntables or stages 49, 50, 51 and 52.

Car 53, similar to the car member 47 is supported by suitable wheels such as 54 resting on and adapted to traverse a pair of rails 55 which are supported by the second step 35, when the apparatus is in its extended position. The rails 55, and through them the car 53, are adapted to be supported by a suitably arranged rest 56 when the apparatus is in its collapsed position so that the car 47 will be alongside the car 53 and the platforms 49 and 50 will be telescoped.

In the same manner the car 57 is supported by suitable wheels 58 which are adapted to traverse rails 59 which are in turn suitably supported by the third step 36 when, as before, the apparatus is in its extended position. When the apparatus is in its collapsed position the rails 59 are supported by a rest member 60 adjacent the rest 56.

The car 61 is suitably supported by depending flanges 62 which carry the wheels 63. Wheels 63 are adapted to be supported by and traverse the rails 64 which are supported by the fourth step 37 when the apparatus is in its extended position, and by the rest 65 adjacent the rest 60 when the apparatus is in its closed position. It is to be understood that the cars 47, 53, 57 and 61 are annular vehicles adapted to rotate about the member 8 as a center.

In the operation of this device when liquid is forced through the pipe 33 it comes into contact with the piston head of the cylinder 7 and forces it upward, which in turn advances the hanger 9. The step 34 and its associated platform 49 are raised above the platforms 50, 51 and 52 until such a point is reached when the step 35 of the hanger 9 comes in contact with the rails 55 and lifts them from off the rest 56. The stage 50 is then elevated above the stages 51 and 52, until the step 36 comes in contact with the rails 59 and advances them from off the step 60 thus lifting the stage 51 away from the stage 52 until finally the step 37 picks up the rails 63 from off of the rest 65 and elevates the stage 52 from the floor level. Thus the stages 49, 50, 51 and 52 are held in stepped relation one to the other.

When pressure is released through pipe 33 the cylinders are collapsed by gravity. The stage 52 will first come to rest as the rails 64 once again contact the rest 65, and the other three stages 51, 50 and 49 will follow in that order until once again the four stages are completely telescoped and form a single large stage.

Referring to Fig. 2, the construction of a supporting car will be described in detail. This car is similar in all respects to the cars 47, 53, 57 and 61. The car of Fig. 2 consists mainly of a supporting base 70 depending from which are a series of flanges 71 and 72 which support bearings 73 and 74. Car wheels 75 and 76 rotate about axles 77 and 78 which are supported by the bearings 73 and 74 respectively. The wheels 75 and 76 traverse the rails 79 and 80. These rails 79 and 80 form a circular track as shown in Fig. 3. The rails 79 and 80 are supported by channel irons 81 and 82 which are tied together by any suitable cross strut members, such as 83, forming a rigid carriage.

Mounted on the base 70 is a car body formed

of the walls 84 and 85 and joined together at the top by a flooring member 86 which forms the stage or platform such as the platforms of the members 49, 50, 51 and 52, upon which actors may perform. The carriage body is held substantially rigid by means of suitable cross strut members 87, 88 and 89.

A pipe member 90 is supported adjacent the wall 85 by means of a collar 93 suitably attached to the channel iron 82. The uppermost end of the pipe 90 terminates in a nozzle 91 which overlaps the lip of a trough member 92. The lower end of the pipe 90 is in the form of a flexible hose (not shown) which is led to any suitable supply line at the base of the apparatus 1, as will be well understood.

A trough member similar to the trough 92 conforms to the inner annulus of each of the concentric stages 49, 50, 51 and 52. Water is supplied to trough 92 through the pipe 90 which remains fixed relative to the movement of the car members due to its rigid connection to the channel iron 82. Water from the trough 92 flows through any suitable channel (not shown) to a reservoir tank 94 which is supported by the member 87 between the members 84 and 85. There are three tanks (not shown) placed to counter-balance each other and similar to tank 94 for each of the rotating platforms 49, 50, 51 and 52. Projecting into the tank 94 is a feed pipe 95 which forms a source of supply to a centrifugal pump 96. The pump 96 supplies water under pressure to the pipe lines 97, 98 and 99. Water from these lines may be led to any suitable display system around the edges of the platforms 49, 50, 51 and 52, as will be well understood.

In the instant case spray nozzles were concealed within ornaments such as that shown at 100, Fig. 1. These ornaments were placed at suitable intervals around the annulus of the various platforms in order that a continuous sheet of water would be presented, when they were turned on. An annular drain tank 101 is located underneath the platform 86 and returns surplus water (not shown), that may fall on and through the platform 86 from the display system, back to the supply tank 94.

The pump 95 is driven by means of an electric motor 101 mounted on the cross-beam 88 through a suitable positive drive, 102. Motor 101 is connected through a suitable line 103 to contacts 104 which are mounted on the base 70. Contacts 104 withdraw energy from the power rails 105 mounted on and insulated from the cross-beam 88.

The inner wheels 48', 54', 58' and 62'' of each of the platforms, 49, 50, 51 and 52 respectively, are provided with chain members 106, 107, 108 and 109 respectively. These chain members each correspond to the chain member shown at 110 in Figs. 2 and 4. Each of these chain members extends around the periphery formed by the innermost wheels of each platform. Each platform is driven by means of an individual driving gear in contact with the chain members 106, 107, 108 and 109 in a manner that will be described below.

As shown in Fig. 3, the platform 49 is driven by means of the motor 127. The platform 50 is driven by means of the motor 112. Platform 51 is driven by means of the motor 113 and a similar motor (not shown) drives the platform 52. The motor construction and mounting is similar in each case.

An electric motor 114 (Figs. 4 and 5) is suit-

ably mounted between the rails 79 and 80 by means of hanger bars 115 and 116 attached thereto. The motor 114 is coupled to a train of variable transmission gears 117 by means of a flexible coupling 118. Power is transferred from the member 117 to a worm gear 119 through a second flexible coupling 120. Worm gear 119 meshes with a pinion gear 121, journaled to a shaft 122. Shaft 122 is supported by a bearing housing 123 mounted adjacent the member 82.

A sprocket or driving gear 124 is journaled at the upper end of the shaft 122. The teeth of gear 124 mesh with the links of the chain 110. Thus it will be seen that when the motor 114 is energized from any suitable source (not shown) the speed of rotation of sprocket gear 124 will be controlled by means of the variable transmission gear train 117, so that the platform supported by the wheels such as 76 may be rotated in either direction or at any desirable speed at will.

Motor 127 is mounted in a slightly different manner from the other motors 112 and 113, due to the fact that car 47 continually rests on step 34 and therefore motor 127 need not be moved relative thereto. The motor 127, as shown in Fig. 1, is mounted on the member 9 and drives a set of variable transmission gears 111 through a chain connection 126. The gear train 111 is mounted on the step 34 by means of suitable hanger bars 125. Power is transmitted from gear train 111 to a driving gear 128 through a worm gear 129 and a clutch 130. It will be understood that the driving gear 128 meshes with the chain 106. Similarly the driving gear 131 of the motor 112 and the driving gear 132 of the motor 113 mesh with the chains 107 and 108 respectively. Thus the platforms 49, 50, 51 and 52 are each individually rotated, at will, by the use of this device.

Referring now to Fig. 6 there are shown four truss members 9, 135, 136 and 137, each one exactly similar to the other. The members 9, 135, 136 and 137 are mounted on the member 8 and depend therefrom adjacent the telescoping cylinders 2 and 7, as described in connection with Fig. 1. Spaced between the member 9 and the member 135 are the rest members 56, 60 and 65. Spaced between the members 135 and 136 are rest members 138, 139 and 140 similar to the rest members 56, 60 and 65. Similarly between the arms 136 and 137 are positioned the rest members 141, 142 and 143 and between the members 137 and 9 are positioned the rest members 144, 145 and 146. The members 65, 138, 141 and 144 are adapted to support the platform 52 in its rest position. The members 60, 139, 142 and 145 are adapted to support the platform 51 in its rest position, and members 56, 140, 143 and 146 are adapted to support the platform 50 in its rest position. The platform 49 is continuously supported by the step 34 integral with the members 9, 135, 136 and 137, as described above. Thus the platforms 49, 50, 51 and 52 are alternately supported by the rest members 56, 60, 65 and 138 to 146 when the apparatus is collapsed and the stages are nested, or by the hangers 9, 135, 136 and 137, when the apparatus is in its extended position.

Referring to Fig. 7, liquid under pressure is supplied to the opening 33 by means of a pipe (not

shown) connected at one end to a three-way valve 150 through a suitable meter 151. The valve 150 is connected to an exhaust pipe 153 through a control valve 154. The liquid supply under pressure to the valve 150 is through a main line 155. A gauge 156 and an auxiliary check valve 157 are located in the main pipe line 155 in front of the valve 150. A manually operable handle 158 controls the supply and exhaust from the valve 150. Any relative position of the cylinders 2 and 7 may be maintained by movement of the handle 158, which in one position permits liquid under pressure from the main line 155 to flow into the cylinder 2 and through contact with the piston head 17 raise the cylinder 7, or in another position it allows liquid to escape from the cylinder 2 through the exhaust line 153 and the cylinder 7 will be carried down by gravity to its rest position.

It will be seen that the platforms 49, 50, 51 and 52 may be individually rotated at will. They may be extended or telescoped during rotation thereof and the hydraulic display system may be controlled to present either a tremendous mass of falling water or a gentle fall as may be desired.

Thus by various combinations of these elements it is possible to produce and photograph many pleasing and unusual scenes. It is to be understood that the controls for the various elements may be all located at a central control board under the direction of one operator, (not shown) without departing from the spirit of the invention.

Having thus described the invention what is claimed as new and desired to secure by Letters Patent is:

I claim:

1. A theatrical platform for motion pictures comprising a plurality of concentric telescoping stages, a hydraulic display system individual to each of said concentric stages, means for successively extending and telescoping said stages, said means comprising a hydraulic lift, and means for rotating said stages, said last-mentioned means comprising a motor and gear train individual to each of said stages.

2. A theatrical stage comprising the combination of a base, a plurality of concentric supports carried thereby and arranged at different elevations and each thereof adapted to support an annular stage, a hydraulic lift having a plurality of annular supports spaced apart, and a plurality of concentric rotatable stages each thereof being adapted to be lifted by one of the concentric supports on said hydraulic lift when said hydraulic lift is extended and adapted to be supported by one of said first mentioned annular supports when said hydraulic lift is retracted.

3. A theatrical stage comprising the combination of a plurality of concentric stages, a base for supporting said stages with said stages nested in certain relative positions, an elevator for lifting said stages from said base with said stages in other relative positions, each of said stages comprising wheels for rotatably supporting said stages, a track for said wheels, and a motor for driving said wheels whereby said stages are adapted to be rotated when supported by said base and also when supported by said elevator.

ROBERT LEWIS GEIB. 70
